CAB FOR TRACTORS OR THE LIKE

Robert W. Dodge, Wenham, Mass.

Application November 14, 1957, Serial No. 48,456

Term of patent 3½ years

(Cl. D14—27)

Fig. 1

Fig. 2

Figure 1 is a perspective view of a cab for tractors or the like in collapsible position, embodying my new design.

Figure 2 is a perspective view of the design in a raised position, the opposite side being the same as that shown and the rear is conventional.

The broken line showing of a tractor is for purposes of illustration of the cab with a tractor.

I claim:

The ornamental design for a cab for tractors or the like, substantially as shown and described.
